UNITED STATES PATENT OFFICE.

DANIEL J. PRENDERGAST, OF NEW YORK, N. Y., ASSIGNOR TO THE PENNSYLVANIA GLOBE GAS LIGHT COMPANY, OF PENNSYLVANIA.

DESIGN FOR A DOME FOR STREET-LAMPS.

SPECIFICATION forming part of Design No. 27,605, dated August 31, 1897.

Application filed July 23, 1897. Serial No. 645,738. Term of patent 14 years.

To all whom it may concern:

Be it known that I, DANIEL J. PRENDERGAST, of the city and county of New York, State of New York, have invented a new and original Design for a Dome for Street-Lamps, of which the following is a specification.

My design is illustrated in the accompanying drawings, in which—

Figure 1 is a plan view of a dome for a street-lamp embodying my design, and Fig. 2 is a vertical sectional view of the same on the line *x-x* of Fig. 1.

The design resides in the shape of the dome, which consists of a dome-shaped body A open at the top at B, with an annular upturned flange C extending about the opening, and having adjacent to the base a substantially upright annular portion D, connected with the dome-shaped body A by an annular shoulder or ledge E.

It will thus be observed that the dome is composed of a lower cylindrical portion D and an upper dome-shaped portion A of smaller diameter at the base than the cylindrical portion D, with which it is connected by the annular ledge E, which forms a shoulder or offset extending about the dome.

Having now described my invention, what I claim as new, and desire to secure by Letters Patent, is as follows:

The design for a dome for streets-lamps substantially as herein shown and described.

In testimony of which invention I hereunto set my hand.

DANIEL J. PRENDERGAST.
